UNITED STATES PATENT OFFICE.

HELEN CECILIA MARGARET FRANKS, OF BROOKLYN, NEW YORK.

METHOD OF PRESERVING FRUITS AND VEGETABLES FRESH.

1,232,271.

Specification of Letters Patent.

Patented July 3, 1917.

No Drawing.

Application filed April 24, 1917. Serial No. 164,120.

To all whom it may concern:

Be it known that I, HELEN C. M. FRANKS, a subject of the King of Great Britain, residing at No. 1 Alice Court, Brooklyn, borough of Queens, State of New York, have invented certain new and useful Improvements in Methods of Preserving Fruits and Vegetables Fresh, fully described and represented in the following specification.

10 The object of this invention is to treat fruits, vegetables, and such perishable articles with a germ destroying or inhibiting gas, as carbon dioxid (CO_2) in such a practical and economical manner, that at a relatively small expense, the articles may be preserved from decay indefinitely, and retain their original appearance and flavor; without which their food value would be materially diminished.

15 Where it is required to keep the articles fresh for only a relatively short time, as a month or two, and at a more or less even temperature and humidity, a charge of the CO_2 gas is applied once under a considerable pressure to the articles, and the pressure repeated after a gradual exhaustion of the first charge. No heat is used in my method of preserving, as the very object of my methods is to preserve the natural qualities 20 of the articles unchanged.

25 When it is required to preserve the fruit for a long time, as on a voyage or journey in which it will be carried through various latitudes, and thus exposed to differences of temperature and humidity, the first charge of CO_2 gas is extracted from the articles by a partial vacuum before the second charge of CO_2 is applied; and other charges of CO_2 and of nitrogen are applied to the articles 30 at carefully graduated pressures, which charges completely remove any tendency to decay or fermentation under any conditions.

35 During the treatment, the articles are packed in suitable separate permanently charged containers of any suitable size and material. Each container has an independent open communication with the atmosphere, and any required number of such containers is inclosed in a tight chamber of 40 suitable size and strength to receive them, and to sustain the pressure at which the gas is applied. Each container is provided with means to hermetically seal it in a partial

vacuum at the close of the treatment, and means is provided within the chamber to seal 55 all the containers before they are brought out into the air.

I am aware that it has been proposed to use CO_2 as a preserving agent, but its successful or effective use requires that the pressure of its application should be great, but applied in such a manner as not to crush the fruit; and its withdrawal effected in such a manner as not to expand and rupture the fruit, and the mere suggestion of its use is 60 of no real value.

To be effective, the present invention includes various specified steps, practised in a prescribed manner, which long experiment has shown are essential to the practical and 70 successful preservation of the fruit or vegetables.

The mere immersion of the articles in the gas of CO_2 is valueless, as the pores and interstices of the article must be penetrated by 75 the gas, to completely eliminate the air and obnoxious germs, and effectively preserve the fruit.

Too low a pressure is therefore inadequate, and too high a pressure is injurious and 80 expensive to generate; wherefore repeated experiments were necessary to determine the lowest efficient pressure, and the safe mode of applying it.

By such means I have determined that a 85 pressure of 60 lbs. per square inch for CO_2 , applied in a certain manner, is necessary to protect such articles effectively from change, and that such pressure may be safely applied by observing the following rules, which 90 were also ascertained by repeated experiments.

The term "process" is used herein to include all the successive treatments, specified in any claim, by subjecting the article to the pressure of a gas or to the exhaustion of air and gases from its tissues. The term "treatment" will be understood as applicable to any one step in the process.

To meet commercial requirements, the 100 tightly closed chamber receiving the gas under a pressure of 60 lbs. pressure per square inch is made of suitable size to admit a large number of containers, as glass jars or tin cans, and to support them in proper 105 connection with sealing mechanism, which

can be actuated from the exterior of the chamber while a vacuum is maintained therein.

I have described one method of treating the articles, and another method which is a specific form of the first method involving additional treatments, which will preserve the fruit or vegetable articles indefinitely.

The method for a partial preservation of the fruit I call "method A," and practice it as follows:

The containers permanently charged with the fruit or vegetables to be treated, being thus arranged in the chamber, the CO₂ gas is introduced and the pressure gradually increased, for a period of ten to twenty minutes, to a pressure of 60 to 70 lbs. per square inch, which is maintained for twenty minutes. This pressure is very gradually reduced to atmospheric pressure, allowing twenty to thirty minutes for the CO₂ gas in the articles to escape.

This step removes from the chamber much of the air first contained therein; but a partial vacuum (one-half of the atmospheric pressure or 16 inches of mercury) is necessary to remove the air more completely, and I therefore generate such vacuum within the chamber very gradually for a space of ten to twenty minutes, thus avoiding any rupture of the skin of delicate fruit, as ripe peaches. I then again supply CO₂ to this exhausted chamber, carrying the pressure very gradually for twenty minutes to 60 lbs. per square inch, as before.

I subject the articles to this gas for a period of one hour after it has attained that pressure, and then very, very slowly discharge this gas, with any mingled air, and exhaust the chamber to a vacuum of at least sixteen mercury inches.

It is exceedingly needful that this exhaustion of the chamber be effected steadily at a uniform rate, as any pulsations in the atmosphere of the chamber, which a vacuum pump may produce, is very detrimental to the fruit from which the gas and air are being extracted during such exhaustion. Sudden pressure may crush the fruit, but the danger from pressure is not half so serious as that from sudden or uneven or too quick evacuation.

When the final vacuum has been gradually attained, the containers are sealed in such vacuum within the chamber in a rarified atmosphere of CO₂ while protected from any exposure to the outer air; and the two pressures of the CO₂ will be found sufficient to preserve such articles for one or two months as the treatments, by the gas and exhaustions, operate to displace nearly all the air or gases in the tissues of the articles, and replace them with the preservative gases. Further treatments may be applied when the articles are to be kept for a long period or in-

definitely, and in such case I call the process method B.

In method B, which is a specific form of the invention, I charge a third time with the CO₂ at 60 pounds per square inch, and then with nitrogen gas at 20 pounds per square inch, such method embracing the following steps:

First, the treatment with CO₂ gas maintained for not less than twenty minutes;

Second, the production of a vacuum of about 16 inches of mercury;

Third, the treatment with CO₂ continued for about one hour;

Fourth, the production of a vacuum of at least 16 inches of mercury;

Fifth, a third treatment with CO₂ at 60 pounds pressure continued for several hours;

Sixth, the production of a partial vacuum to exhaust such nitrogen gas from the articles; and,

Seventh, the treatment of the articles with nitrogen gas at 20 lbs. for a period of three hours, and this gas is then very slowly drawn off and the chamber exhausted to 16 inches of mercury, and the containers sealed in the remaining nitrogen atmosphere. This treatment insures the fruit from alteration or decay under any and all conditions.

This "method B" subjects the articles to gas pressure four times; three times to CO₂ at 60 lbs. pressure, and once to nitrogen gas at 20 lbs. pressure; but substantially the same efficient result can be secured in a third method by using nitrogen gas in both the last two treatments, with a complete evacuation of the chamber intermediate to the two. This method I call "method C."

It will be observed that in the treatments for preserving the article a moderate length of time, the two gas pressures are exerted for periods of 20 minutes and 1 hour, respectively, but that for preserving the article indefinitely two further treatments are applied and the pressure in each maintained for 3 hours. Such treatment under pressure for a total of 6 hours obviously produces a far greater effect upon the article than the two treatments of 1 hour and 20 minutes applied for preserving the article for use within a month.

The sealing of the containers while inclosed in the chamber is effected by providing the lid or closure of each container with an inlet having means to tightly seal it; and such means may afford an opportunity to strengthen the said seal by solder or otherwise, after the containers are removed from the chamber.

Having thus set forth the nature of the invention what is claimed herein is:

1. In the preparation of fruits and vegetables to preserve the same, the process herein described, consisting in twice subjecting the fruits or vegetables to CO₂ gas at a

pressure between 60 and 70 pounds per square inch for twenty minutes to one hour respectively, and after each application of the CO₂ subjecting the fruits or vegetables 5 to a vacuum of 16 inches of mercury and finally sealing them in a vacuum.

2. The process of preserving fruits and vegetables, which consists in inclosing in a tight chamber a container charged permanently with the fruit, the container having 10 an open communication with the atmosphere of the chamber and means adapted for hermetically sealing the same, forcing CO₂ into the chamber to a pressure between 60 and 15 70 pounds per square inch, maintaining such pressure for at least ten minutes, then very slowly discharging the CO₂ and the air mixed therewith, to atmospheric pressure, then exhausting the chamber very 20 gradually, then very gradually for about 15 minutes renewing the CO₂ to a pressure between 60 and 70 pounds per square inch and maintaining the pressure of such CO₂ upon the fruit for at least one 25 hour, then very slowly discharging the gas and mingled air from the chamber, and excluding the air therefrom, and sealing the container within the chamber before removal therefrom.

30 3. In the treatment of fruits and vegetables in a plurality of containers simultaneously within a single chamber, the containers being permanently charged with the articles to be treated and constructed to be sealed, and having independent open communication with the atmosphere in the chamber, that process which consists in subjecting the entire contents of the chamber to CO₂ at a slowly generated pressure between 60 and 70 pounds per square inch, maintaining such pressure not less than ten minutes, slowly discharging such gas and air mingled therewith, very slowly exhausting the chamber to a vacuum of 16 inches 40 of mercury, then supplying CO₂ to this exhausted chamber, carrying the pressure very gradually to at least 60 pounds per square inch, maintaining such pressure for at least one hour, slowly discharging the gas 45 under pressure in the chamber and again exhausting the chamber to a vacuum of at least 16 inches, and finally closing the containers within the said chamber before removal therefrom, to protect their contents 50 55 from the atmosphere.

4. The process of preserving fruits and vegetables, which consists in subjecting the fruits and vegetables in a tight chamber, first, to an atmosphere of CO₂ under a pres-

sure of about 60 pounds per square inch 60 and afterward discharging such pressure and subjecting the fruit to nitrogen gas at a pressure of not less than 20 pounds.

5. The process of preserving fruits and vegetables, which consists in inclosing the 65 container, permanently charged with the fruit, in a tight chamber, forcing CO₂ into the chamber to a pressure of 60 to 70 pounds and maintaining such pressure for three hours, discharging the CO₂ and mingled air 70 from the chamber and exhausting the chamber to at least one-half the atmospheric pressure, then forcing nitrogen at not less than 20 pounds pressure per square inch into the chamber and maintaining such 75 pressure of nitrogen gas for three hours, then discharging the nitrogen gas and partially exhausting the chamber, and sealing the receptacle in such partial vacuum before removal from the chamber.

80 6. The process of preserving fruits and vegetables, which consists in inclosing in a tight chamber a container permanently charged with the fruit, the container having an open communication with the atmosphere 85 of the chamber and means adapted for hermetically sealing the same, forcing CO₂ into the chamber to a pressure between 60 and 70 pounds per square inch, maintaining such pressure for ten or twenty minutes, then 90 very slowly discharging CO₂ and the air mixed therewith to atmospheric pressure, then exhausting the chamber very gradually, to 16 inches mercury, then very gradually during a period of fifteen minutes renewing the CO₂ to a pressure between 60 and 70 pounds per square inch and maintaining the pressure of such CO₂ upon the fruit for one hour, then for a period of fifteen minutes slowly discharging the gas 95 100 and mingled air to atmospheric pressure, the reduction in pressure being steady and uniform to prevent injury to the tissues of the fruit, then renewing the CO₂ at a pressure of 60 to 70 pounds per square inch and maintaining such pressure to operate upon the fruit three hours, then discharging the gas and mingled air, and forcing nitrogen gas into the chamber to a pressure of 20 pounds per square inch and maintaining 105 such pressure for three hours, then removing the nitrogen gas and creating a vacuum of sixteen inches of mercury and sealing the 110 container in such vacuum.

115 In testimony whereof I have hereunto set my hand.

HELEN CECILIA MARGARET FRANKS.
